PATTERN POSITIONING DEVICE

John A. Strommen, Milwaukee, Wis., assignor to
Allis-Chalmers Manufacturing Company, Milwaukee, Wis.

Application January 14, 1952, Serial No. 266,396

5 Claims. (Cl. 22—23)

1

This invention relates to molding apparatus and is more particularly concerned with the provision of apparatus for effectively utilizing a pattern segment in the formation of molds.

In one of its aspects, the present invention is of particular advantage, although not in any manner limited, in the production of annular molds. Annular molds have heretofore been made by using a segmental pattern and rotating it around its center in steps, sand being packed against the circumferential outer surface of the pattern at each step. This type of pattern has previously been made up of at least two separate parts, so assembled that manual removal of one part, which is usually in the nature of a wedge, is necessary before the other part can be withdrawn from the mold. Insertion of the wedge functions to correctly position the other part of the pattern in a predetermined relation to a surrounding mold flask or other suitable structure.

The cost involved in using patterns comprising complementary parts, at least one of which is a wedge, is excessive because a completely new pattern comprising the two parts is required for each mold having a materially different diameter. Moreover, wedge parts which are usually driven into place, soon become damaged or worn sufficiently to require frequent replacement. In addition, a high degree of skill and considerable effort are required in effectively utilizing such patterns and consequently the labor cost is high.

The present invention has as an object to provide apparatus for effectively utilizing a pattern segment in an improved manner minimizing the time, effort and skill necessary for the production of satisfactory molds.

Another object of this invention is the provision of apparatus for effectively positioning and manipulating pattern segments of different sizes whereby the cost of providing patterns for molds of different dimensions is greatly reduced, in that only the unitary pattern segment need be changed.

Still another object of the present invention is the provision of apparatus of the foregoing type which affords the advantage of being fool-proof in operation, which is simple and inexpensive to construct and maintain, and which affords ready adjustment of the position of a pattern segment associated therewith.

Other objects and advantages will appear from the following description of a structure illustrating an embodiment of the invention, reference being had to the accompanying drawings, in which:

Fig. 1 is a top view of an apparatus embodying

2

the invention with a pattern segment disposed in its mold forming position;

Fig. 2 is a top view similar to Fig. 1 showing the pattern segment in its innermost position relative to the mold;

Fig. 3 is a top view similar to Fig. 2 showing the position of the pattern segment after counter-clockwise rotation of the same through an angle of nearly 90°;

Fig. 4 is a top view similar to Fig. 3 showing the pattern segment disposed in its next mold forming position;

Fig. 5 is a vertical section taken along line V—V of Fig. 4;

Fig. 6 is a vertical section taken along line VI—VI of Fig. 3;

Fig. 7 is an enlarged top view similar to Fig. 1 with the flask omitted in the interest of clarity and with the pattern segment shown as an integral part of a hub portion of the pattern moving mechanism;

Fig. 8 is an enlarged top view similar to Fig. 7 with the pattern shown in its innermost position in conformity with Fig. 2;

Fig. 9 is a vertical section taken along the line XI—XI of Fig. 8 with the wrench and a portion of the pattern segment omitted in the interest of clarity; and

Fig. 10 is a schematic diagram showing essential coacting parts of the pattern positioning apparatus in proper working position.

As shown in the drawings, an apparatus embodying the invention comprises an arcuate pattern segment 1 rigidly secured to a split hub member 2, which is held together by bolts 3 and nuts 4 which coact with flange portions of said split hub. It is usually preferable to detachably secure segment 1 to split hub member 2 by any suitable means, which is designated generally by the numeral 5. An eccentric collar 6 is journaled

40 for rotation in split hub 2, and is rotatably disposed on a vertical spindle 7 which is rigidly supported in a spindle receptacle 8. Receptacle 8 is fixedly secured to a moldboard or other suitable surface 9 forming the bottom of flask 11.

Eccentric collar 6 is provided with a pair of recesses 12 in its outer surface, which are adapted to receive complementary projections on a special collar rotating wrench 13 as shown in Figs. 7 and 8.

50 A collar stop peg 14 is rigidly fixed in split hub 2 so that it is coactable with the opposite ends or shoulder portions 16 of a protruding flange 17 on collar 6, as best shown in Figs. 7 and 8. Items 14, 16 and 17 may be considered as means 55 for limiting rotation of collar 6 relative to hub 2,

since the rotational limits of collar 6 relative to split hub 2 are reached when one or the other of ends 16 of flange 17 engages stop peg 14. The eccentric collar 6 is provided with a lip portion 18, which coacts with split hub 2 and prevents eccentric collar 6 from slipping, in response to gravity, through split hub 2 and out of contact with it.

In operation, the entire assembly, which comprises the elements 1, 2, 6, 7, and associated parts, is centrally disposed in the flask 11, and eccentric collar 6 is rotated to place pattern segment 1 in its maximum radially outward position as governed by the coaction of flange 17 and stop peg 14.

While the assembly aforementioned is in this position, side boards 19 are placed against the edge of pattern 1 and pushed radially outward against the inner surface of flask cheek 21. Next, molding material is packed in the space defined by the outer peripheral surface of pattern 1, the inner surface of flask cheek 21, and the side boards 19. After this packing operation is completed, side boards 19 are removed, and eccentric collar 6 is preferably rotated to its maximum radially inward position, which in the case of the present invention is 135°. This positions the apparatus as shown by Fig. 2.

If desired, a smaller angular rotation is permissible, this being determined by the amount of clearance which must be provided between the pattern and the mold in order to conveniently allow for rotation of the pattern. When using a 90° pattern segment, the collar 6 should be 45° from the position it would be in if it were to have its thickest or maximum eccentric portion between its center of rotation and the circumferential midpoint of the pattern segment against which molding material is to be packed. This positioning insures that the pattern segment will not be jammed into the packed molding sand as the eccentric collar is rotated to cause withdrawal of the pattern segment. Assume collar 6 initially positioned so that its maximum eccentric portion is between the center of rotation of the collar and the circumferential midpoint of the pattern segment. When the eccentric collar is rotated from its initial position counterclockwise to cause withdrawal of the pattern segment, the edge of the pattern segment adjacent the radial edge B, as shown in Fig. 10, will move to the left at a faster rate than it will withdraw inwardly and it will be jammed into the packed molding sand damaging the mold. Damage to the mold can be obviated by designing the pattern segment so that the circumference of the pattern segment is concentric to the periphery of flask 11 when the thickest portion of collar 6 is at least 45° from the position it would be in if its thickest portion were between its center of rotation and the circumferential midpoint of the pattern segment. This allows the edge of the pattern segment adjacent to the radial edge B to move inward at a faster rate than to the left when the eccentric collar is rotated to cause withdrawal. As a result, the pattern segment is cleanly withdrawn from the mold surface without damaging it. In Fig. 10, the circumference of pattern segment 1 is concentric to center point F and therefore concentric to the periphery of any flask having a center of arc at point F, although the thickest portion of collar 6 is located at point A. Generally, if a pattern segment covering more or less than 90° is to be used, the eccentric collar 6 can be allowed to approach no closer to its full radially outward

position than half the number of degrees covered by the pattern segment.

Next the pattern and its associated assembly is rotated in flask 11 around spindle 7. The extent of this rotation is preferably slightly less than the number of degrees covered by the pattern segment so as to effect an overlapping of the pattern with the previously packed molding material as shown in Figs. 3 and 6. When this has been done, eccentric collar 6 is rotated to a maximum radially outward position governed by the coaction of flange 17 and stop peg 14. One side board 19 is placed against the open edge of pattern 1 and pushed radially outward against the inner surface of flask cheek 21, after which sand is packed in the space between pattern 1, flask cheek 21, side board 19, and that part of the mold previously formed in the first operation. This results in an arrangement of the apparatus such as shown in Figs. 4 and 5.

The steps just described are repeated until pattern segment 1 has made a complete revolution around spindle 7 and a circular mold has been formed in flask 11. This completes the formation of a circular mold such as is indicated in the drawings, whereafter the flask and mold forming apparatus are removed as desired.

In Fig. 10, the pattern segment 1 is shown in its ramming position with the point of maximum eccentricity A on collar 6 disposed in radial alignment with the true center of rotation F of pattern segment 1 and a selected radial edge B of the segment. Obviously the point of minimum eccentricity C on collar 6 will always be spaced 180° from the point of maximum eccentricity A. The other radial edge D of pattern segment 1 is spaced X° in a counterclockwise direction from the point of minimum eccentricity C on collar 6. Consequently collar 6 can be rotated 2X° in a counterclockwise direction from the position shown in Fig. 10 without effecting any change in the angular position of segment 1. That this is so is obvious, when it is considered that during rotation through an angle of X° in this direction from the position shown, radial edge D will move inward until point C is in radial alignment with segment edge D, and that during the next X° of rotation in the same direction, radial edge D will move outward until a point G on collar 6, which is equally as eccentric as the point E thereon, is disposed in radial alignment with segment edge D. A further rotation of eccentric collar 6 in the same direction is impractical for making molds as it will obviously force that portion of the outer face of the segment adjacent radial edge D outward beyond its initial position.

The foregoing demonstrates that in the formation of annular molds the maximum permissible angle of rotation of eccentric collar 6 relative to pattern segment 1, when the latter is in its proper mold ramming position, is always 2X°, i. e., twice the angle enclosed between the radial lines FE and FC. The arcuate pattern segment 1, when expressed in terms of the angle included between lines FE and FC is always equal to 180°-X°. Now, if MR_c designates the maximum angle of rotation of collar 6 relative to pattern segment 1, MR_c=2X° and, if S designates the angle of the arcuate pattern segment 1, then S=180°-X°, which may be written X°=180°-S. Since MR_c=2X° it is further apparent that

$$MR_c=2(180^\circ-S),$$

which is the same as MR_c=360°-2S.

Thus the maximum practical rotation of pat-

tern segment 1 can never exceed the included angle of the segment because a rotation of segment 1 through a greater angle than that aforementioned will leave a gap between the lagging radial edge of segment 1 and the adjacent end of the mold section previously formed. Therefore, nothing is to be gained by adopting an arrangement affording a rotation of segment 1 in excess of the angle which is encompassed by its arcuate surface. In fact, the lagging edge of segment 1 preferably overlaps the adjacent end of the previously formed mold section to insure the formation of a mold having a flawless inner surface and to prevent breaking away of the adjacent edge of the previously formed mold during the succeeding ramming operation. Consequently, as a practical matter, the maximum rotation of pattern segment 1 (MR_s) should never exceed the angle encompassed by pattern segment 1 (S). The maximum pattern segment rotation (MR_s) relative to eccentric collar 6, after the collar has been rotated through its maximum angle of rotation (MR_c), is equal to MR_c or $2X^\circ$, as previously explained. This fact may be confirmed by observing that during rotation of segment 1 relative to collar 6 through an angle of X° in the same direction in which collar 6 was rotated, radial edge D will move inwardly from point G on collar 6 until it is in radial alignment with the point of minimum eccentricity C thereon, and during the ensuing rotation of X° in the same direction, radial edge D will move outward until it falls in radial alignment with point E on collar 6, which is equally as eccentric as point G thereon, and which therefore positions radial edge D in its initially radially outward position. A further rotation of pattern segment 1 relative to eccentric collar 6 is impractical for making molds as it will obviously force that portion of the outer face of segment 1, adjacent radial edge D, outward beyond its proper mold forming position.

Since $MR_s=2X^\circ$, and since $MR_c=2X^\circ$ as proven earlier, it follows that $MR_s=MR_c$. Now, since MR_s should never exceed S as previously explained, for all practical purposes $MR_s=S$. This being so, formula $MR_c=360^\circ-2S$ may be written $S=360^\circ-2S$, or $3S=360^\circ$. Solving this formula, S, MR_s , and MR_c all equal 120° .

A pattern segment of 120° is the largest which can be advanced from its initial ramming position to its next ramming position so that the full arcuate extent of the segment is presented in continuous mold forming relation to the previously rammed mold section, in only two steps. This two step process is accomplished by first rotating eccentric collar 6 (120°) relative to pattern segment 1 and then rotating segment 1 (120°) relative to collar 6. Obviously a smaller pattern segment may be effectively used in a similar manner. In addition a larger segment may be effectively moved from one practical ramming position to the next in either of two ways: (1) rotation of eccentric collar 6 relative to pattern segment 1 through an angle somewhat less than MR_c , followed by simultaneous rotation of eccentric collar 6 and pattern segment 1 as a unit, relative to the contemplated mold until the full arcuate extent of segment 1 is spaced inwardly from its ramming position, in turn followed by rotation of eccentric collar 6 relative to pattern segment 1 in an opposite direction until the segment is moved radially outward into its ramming position; and (2) rotation of eccentric collar 6 through an angle somewhat less than MR_c rela-

tive to pattern segment 1, followed by rotation of segment 1 through an angle somewhat less than MR_s , followed by a consecutive repetition of these two operations until the full arcuate extent of segment 1 is spaced inwardly from its ramming position, after which collar 6 must be rotated relative to segment 1 in an opposite direction until segment 1 is moved radially outward into its ramming position.

As a practical matter, the size of the pattern segment should be as large as possible in order to complete a mold with a minimum number of separate ramming operations, and yet the segment should be small enough to be readily withdrawable from the inner surface of a mold section a distance such that the segment can be easily and quickly rotated from one ramming position to another without causing damage to the previously formed mold section. The positioning apparatus of the present invention is designed for use with pattern segments of somewhat less than 180° , and therefore, it follows that a minimum of three separate ramming operations must be executed before a complete annular mold can be formed therewith.

Although a pattern segment of 120° is theoretically workable, actually, to obtain a practical degree of overlap, as previously pointed out, a pattern segment of 120° requires four ramming operations. The fact that the human factor is involved, makes it desirable to use a segment less than 120° to avoid a simultaneous or step-by-step pattern shifting procedure previously described as being possible. Furthermore, the smaller segments are less costly to build and more convenient to use. Experience in forming circular molds of 7 to 8 feet in diameter has shown a 90° pattern segment to be of satisfactory utility even though such a segment requires five separate ramming operations (allowing for overlap for each ramming operation) in order to complete an annular mold.

From the foregoing it should be obvious to one skilled in the art that the present invention affords a simple, economical and trouble free apparatus for forming molds with a unitary pattern segment and that it may be successfully practiced with apparatus differing somewhat from the practical construction herein shown and described for purposes of illustration. Accordingly it is to be understood that the invention is not intended to be limited to the exact details of construction, combination, and/or operation herein set forth, as various modifications thereof, within the scope of the appended claims, may occur to persons skilled in the art.

It is claimed and desired to secured by Letters Patent:

1. An apparatus for forming a mold having an inner arcuate face equidistant from the center of arc thereof, said apparatus comprising: a spindle fixedly positionable at said center; an eccentric collar mounted on said spindle for rotation therearound, said collar having a maximum eccentric portion; and a pattern segment presenting an arcuate surface for forming said face, said segment being mounted on said eccentric collar for rotation therearound and being movable in a general radial outward direction into a mold-forming position in response to a rotation of said collar in a direction effective to move said maximum eccentric portion through an arc from a point lying outside a central angle subtended by said arcuate surface to a point lying on a radial line extending from said center to a terminal

point of said arcuate surface, said arc subtending at said center a second angle adjacent to said central angle, and said segment presenting in said mold-forming position said arcuate surface equidistant from said center.

2. An apparatus for forming a mold having an inner arcuate face equidistant from the center of arc thereof, said apparatus comprising: a spindle fixedly positionable at said center; an eccentric collar mounted on said spindle for rotation therearound, said collar having a maximum eccentric portion; a hub member having a pattern segment attached thereto presenting an arcuate surface for forming said face, said segment being mounted on said collar for rotation therearound and being movable in a general radial outward direction to place said arcuate surface in a mold-forming position in response to a rotation of said collar in a direction effective to move said maximum eccentric portion through an arc from a first point lying outside a central angle subtended by said arcuate surface to a second point lying on a radial line extending from said center to a terminal point of said arcuate surface, said arc subtending at said center a second angle adjacent to said central angle, said segment presenting in said mold-forming position said arcuate surface equidistant from said center; and stop means having relatively engageable parts, one of said parts being mounted on said collar and the other of said parts being mounted on said hub member, said parts being effective upon being brought into engagement to stop said movement of said maximum eccentric portion beyond said second point to prevent said maximum eccentric portion from being interposed between said spindle and said arcuate surface in the area of said central angle.

3. An apparatus for forming a mold having an inner arcuate face equidistant from the center of arc thereof, said apparatus comprising: a spindle fixedly positionable at said center; an eccentric collar mounted on said spindle for rotation therearound, said collar having a maximum eccentric portion; a hub member having a pattern segment attached thereto presenting an arcuate surface for forming said face, said segment being mounted on said collar for rotation therearound and being movable in a general radial outward direction to place said surface in a mold-forming position in response to a rotation of said collar in a direction effective to move said maximum eccentric portion through an arc from a point lying outside a central angle subtended by said arcuate surface to a point lying on a radial line extending from said center to a terminal point of said arcuate surface, said arc subtending at said center a second angle adjacent to said central angle; and stop means having relatively engageable parts, one of said parts being mounted on said collar and the other of said parts being mounted on said hub member, said parts being cooperatively effective to limit relative rotation of said collar with respect to said hub member to prevent said maximum eccentric portion from being interposed between said spindle and said arcuate surface in the area of said central angle.

4. An apparatus for forming a mold having an inner arcuate face equidistant from the center of arc thereof, said apparatus comprising: a spindle fixedly positionable at said center; an eccentric collar mounted on said spindle for rotation therearound, said collar having a maximum eccentric portion; a hub member having a pattern segment attached thereto presenting an ar-

cuate surface for forming said face, said segment being mounted on said collar for rotation therearound and being movable in a general radial outward direction to place said surface in a mold-forming position in response to a rotation of said collar in a direction effective to move said maximum eccentric portion through an arc from a first point lying outside a central angle subtended by said arcuate surface and on a diametral line extending through said center and the center of said arcuate surface to a second point lying on a radial line extending from said center to a terminal point of said arcuate surface, said segment being movable in a general radial inward direction to withdraw said surface from said mold-forming position in response to a rotation of said collar in a direction effective to move said maximum eccentric portion through said arc from said second point to said first point, said arc subtending at said center a second angle adjacent to said central angle; and stop means having relatively engageable parts, one of said parts being mounted on said collar and the other of said parts being mounted on said hub member, said parts being effective upon being brought into engagement in response to said rotation of said collar to limit the maximum relative rotation of said collar with respect to said hub member to prevent said maximum eccentric portion from being interposed between said spindle and said arcuate surface in the area of said central angle.

5. An apparatus for forming a mold having an inner arcuate face equidistant from the center of arc thereof, said apparatus comprising: a spindle fixedly positionable at said center; an eccentric collar mounted on said spindle for rotation therearound, said collar having a maximum eccentric portion; a hub member having a pattern segment attached thereto presenting an arcuate surface for forming said face, said segment being mounted on said collar for rotation therearound and being movable in a general radial direction to place said surface in a mold-forming position in response to a rotation of said collar in a direction effective to move said maximum eccentric portion through an arc from a point lying outside a central angle subtended by said arcuate surface to a point lying on a radial line extending from said center to a terminal point of said arcuate surface, said arc subtending at said center a second angle adjacent to said central angle, and said segment presenting in said mold-forming position said arcuate surface equidistant from said center; and stop means having relatively engageable parts, one of said parts being mounted on said collar and the other of said parts being mounted on said hub member, said parts being effective upon being brought into engagement to limit relative rotation of said collar with respect to said hub member to an angle of 360 degrees minus twice said central angle to prevent said maximum eccentric portion from being interposed between said spindle and said surface in the area of said central angle.
